PURIFICATION OF LONG CHAIN FATTY ACIDS

Evald L. Skau, New Orleans, La., assignor to the United States of America as represented by the Secretary of Agriculture

No Drawing. Application June 25, 1952,
Serial No. 295,594

32 Claims. (Cl. 260—404)

(Granted under Title 35, U. S. Code (1952), sec. 266)

A non-exclusive, irrevocable, royalty-free license in the invention herein described, for all governmental purposes, throughout the world, with the power to grant sublicenses for such purposes, is hereby granted to the Government of the United States of America.

This invention relates to long chain fatty acids and has among its objects separation in a simple manner of a substantially pure long chain fatty acid from mixtures of such acids, and the production of crystalline compounds of the formula $RCOOH.NH_2COCH_3$ where R is the hydrocarbon radical of an aliphatic hydrocarbon monocarboxylic acid having a neutralization equivalent below 360 (such acids, which include both saturated and unsaturated acids, are hereinafter referred to by the term "long chain fatty acids"). The compounds above mentioned are generically referred to as "long chain fatty acid-acetamides," terms like "stearic acid-acetamide," "palmitic acid-acetamide," etc., being used for specific compounds.

A present commercial process of producing long chain fatty acids involves the hydrolysis of glyceridic fats and oils. The acids are by this process produced in the form of mixtures of their saturated and unsaturated homologs.

Known methods of purification, or isolation of an individual long chain fatty acid from such mixtures of homologs, which are feasible for large-scale production, do not give complete separation. As a result numerous commercially available grades of conventionally purified acids, although predominantly the desired acid, are mixtures containing significant amounts of other long chain fatty acids. For example, a commonly used grade of stearic acid contains about 90% stearic, about 6% palmitic, and about 4% oleic acid along with small amounts of other long chain fatty acids.

Purer long chain fatty acids for uses such as in the production of pharmaceuticals, cosmetics, soaps, cold rubber, etc., are in demand. However, further purification by known methods is tedious and expensive. The mixtures of long chain fatty acids have properties such that even fractional crystallization has proven to be inefficient in the isolation of an individual acid therefrom or the separation of the acids from each other unless an oxygenated solvent is used. This inefficiency of fractional recrystallization is probably due to the formation of double molecular compounds crystallizing in the form of crystals containing more than one kind of acid molecule, particularly where a hydrocarbon rather than a more expensive oxygenated solvent is used as the solvent.

The difficulty of isolating a long chain fatty acid in a pure form has also made difficult the identification of a long chain fatty acid contained in a mixture of such acids. When a derivative is prepared of the acid in such a mixture, the derivatives of the homologs which happen to be present are also generally formed. Thus the problems of isolation are merely transferred, usually with added difficulties, to the formed derivative.

In general according to the present invention, the long

2

chain fatty acid is mixed with acetamide to form a liquid single phase solution. This brings the reactants into intimate association whereby they can form the desired crystalline compound. Crystallization of the compound is then caused to take place.

The mixing of the long chain fatty acid and acetamide in a liquid single phase can be accomplished by fusing them together to form a single phase solution in which the substances themselves constitute mutual solvents.

10 Preferably, the acid and acetamide are dissolved in a common solvent, or in a mixture of two or more solvents of such character that the final mixture exists as a single liquid phase solution.

The proportioning of the long chain fatty acid and 15 acetamide may be varied, but it is preferable for efficient operation to mix them in substantially equimolecular proportions.

Preferably, the process is utilized in connection with the separation of a substantially pure long chain fatty 20 acid from a mixture containing a predominate amount of such acid and lesser amounts of other long chain fatty acids. In this process, the mixture and the acetamide are formed into a liquid single phase solution, preferably in equimolecular proportions relative to all the acids 25 present and preferably in an inert solvent to form the liquid single phase solution. The long chain fatty acid-acetamide being separated is then caused to crystallize in the mother liquor, and the crystalline material is separated therefrom.

30 The crystalline material thus obtained is generally readily purified as by recrystallization. Such a purified material is composed of a crystalline compound having the molecular structure $RCOOH.NH_2COCH_3$, where R is the hydrocarbon radical attached to the carboxyl of the 35 particular long chain fatty acid being isolated.

The use of an inert solvent in which both the acid and the acetamide are dissolved facilitates subsequent removal of the crystallized fatty acid-acetamide compound. The formation of the fatty acid-acetamide compound in a

40 liquid single phase inert solvent is therefore preferred. Suitable inert solvents include liquid organic compounds or mixtures thereof which are miscible with and chemically inert to the acetamide and the fatty acids and to the formed fatty acid-acetamide compounds, as for example, ketones, such as acetone and methyl ethyl ketone, alcohols, such as methyl, ethyl, isopropyl and tert-butyl alcohol, esters, such as methyl acetate, ethyl propionate, and amyl acetate, ethers, such as diethyl ether, dioxane and anisole, and hydrocarbons such as pentane, cyclohexane and benzene. Benzene and acetone and mixtures thereof have been found to be particularly suitable.

Crystallization can be caused and the crystalline material separated from the mother liquor by any desired procedure. For example, it may be caused by lowering 55 the temperature, or caused by decreasing the concentration of the solvent, for example, through evaporating off a volatile solvent by raising the temperature, merely leaving the vessel containing the solution standing open, lowering the pressure, or by any combination of such means, or 60 crystallization may be caused by the addition of a selective solvent miscible with the other components but having a lesser degree of solubility for the fatty acid-acetamide being crystallized.

Where an inert solvent is used, the amount of solvent 65 should not, for efficient operation, be in any significant excess, since it is desirable that crystals of the fatty acid-acetamide be caused to form expeditiously, as, for example, by merely lowering the temperature. The range of suitable proportions varies depending on the acid being isolated, different solvents, and the manner it is contemplated that crystallization will be caused. It is a simple

procedure, however, to determine suitable proportions for any given acid or mixture by dissolving a small amount of the acid and acetamide, in the proportions in which they are to be reacted, in the particular solvent to be used; using enough solvent at the desired operating temperature to obtain solution, causing crystallization to take place, and removing and testing the crystalline material to see if it is the desired compound.

The temperature used in forming the liquid single phase containing the long chain fatty acid and the acetamide is not critical. Any temperature above that at which the solution of the acetamide and the acid is undesirably viscous and below the decomposition temperature of the respective reagents is operable.

While the reactions involved are rapid and efficient at normal room temperature, it has been found that mixing the acid and acetamide in the proper proportions in a single liquid phase at a moderately elevated temperature (about 50. to 90° C.) results in the crystallization of adequate amounts of fatty acid-acetamide compounds at room temperature or other readily attainable crystallization temperatures, and the employment of such moderately elevated temperatures is preferred.

The processes can suitably be conducted in either a continuous or a batch-wise manner, the former being preferred in the large scale purification of a long chain fatty acid and the latter in the identification of such acid contained in a mixture of the acids.

Preferably, the long chain fatty acid-acetamides produced by the process of the present invention are those in which R is the hydrocarbon radical attached to the carboxyl group of a long chain saturated aliphatic monocarboxylic acid, such as stearic acid ($R=C_{17}H_{35}$), palmitic acid ($R=C_{15}H_{31}$), myristic acid ($R=C_{13}H_{27}$) or lauric acid ($R=C_{11}H_{23}$). These crystalline compounds are definite structures each molecule of which is composed of one molecule each of acetamide and the acid.

These compounds are valuable for numerous purposes. They provide a readily purifiable crystalline form of the respective acid. They provide a readily identifiable derivative of the acid. They provide a crystalline compound of which the acid is the principal component and from which the acid can be released by dissolving the compound in various solvents (such as hydrocarbons, ketones, ethers, esters, and the like, in which solvents the compound dissociates) or by contacting it with a selective solvent for the acid or for acetamide, e. g., water. This property of dissociation makes the compounds valuable reagents for employment in any reaction involving a long chain fatty acid in a solution in which the presence of acetamide does not lead to undesired side reactions.

The crystalline material provided by the present invention can be readily dissociated into acetamide and the respective acid, and the compounds separated from each other. This can be accomplished by contacting the material with a liquid in which the acetamide is soluble and the acid being separated is less soluble. This results in dissociation and placing the acetamide in solution while the acid remains undissolved and is readily isolated from the solution of acetamide. For example, melting such a fatty acid-acetamide compound composed of a water insoluble acid in contact with water allows the rapid solution of acetamide in water leaving a residue of the less soluble acid. In general, the acids contained in the fatty acid-acetamide compounds provided by the present invention can be readily recovered by merely extracting the compounds with water until all of the acetamide is removed. While such an extraction proceeds most rapidly at an elevated temperature, it can suitably be accomplished at any temperature from 0° C. to the decomposition temperature of the acid.

A more detailed explanation of the preferred process follows: An impure long chain fatty acid, such as commercial stearic acid, can be purified by dissolving it and an approximately equimolar proportion of acetamide, based

upon the neutralization value of the impure acid, in a mixture of benzene and acetone, cooling the solution until crystals form, removing the crystals, as by means of filtration, centrifugation, or the like, purifying the crystals if desired, for example, by recrystallization from the same solvent or from a different solvent, and removing the acetamide, for example, by extracting the acetamide from the crystals by repeated extraction or continuous countercurrent extractions with water. Since when the acid has thus been freed of its homologs it can be readily purified by recrystallization, even from a hydrocarbon solvent, it is often convenient to remove the bulk of the acetamide by the extraction and to remove the remainder of it by recrystallization of the acid.

The following examples exhibit the invention in detail as applied to mixtures of long chain fatty acids:

Example I

32 grams of a commercial stearic acid (consisting of about 90% stearic acid, about 6% palmitic acid, and about 4% oleic acid and having a freezing point of 66.77° C. by the sealed tube method and an iodine value (Wijs) of 2.9) and 7.2 grams of pure acetamide were dissolved in about 20 grams of benzene by warming to about 70° C. The mixture was allowed to cool to room temperature and the crystals which formed were separated from the mother liquor by centrifugation. After evaporation of the residual solvent in vacuo, the crystalline stearic acid-acetamide obtained weighed 31.1 grams.

4.7 grams of this stearic acid-acetamide was subjected to a continuous extraction with hot water in a liquid-liquid extraction apparatus to remove the acetamide and the remaining stearic acid (present as the upper liquid layer, which solidified on cooling) was crushed, and vacuum dried over P_2O_5 . It weighed 4.0 grams. It had a freezing point by the sealed tube method of 68.80° C. (about 0.5° below the freezing point of pure stearic acid), and an iodine value (Wijs) of 0.6, as compared to an iodine value of 0.0 for pure stearic acid.

40.24.9 grams of the stearic acid-acetamide above obtained was recrystallized from 14 grams of benzene by heating to about 70° C. and cooling to room temperature, and 21.2 grams of desolvanted white crystalline stearic acid-acetamide was obtained. The material is referred to below as sample A.

4.8 grams of sample A was extracted with hot water according to the procedure above described, and yielded 3.9 grams of vacuum dried stearic acid. The freezing point of this acid by the sealed tube method was 69.00° C. Its iodine value (Wijs) was 0.1.

16.4 grams of sample A was again recrystallized from benzene. 14.1 grams was obtained. 9.3 grams of the crystalline stearic acid-acetamide so obtained was extracted with hot water according to the procedure above described, yielding 8.5 grams of vacuum dried stearic acid. The freezing point of this acid by the sealed tube method was 68.70° C., and the iodine value was 0.0. Two recrystallizations of 4.5 grams of this stearic acid in 8 cc. portions of pure acetone yielded on desolvantizing 4.0 grams of stearic acid having a freezing point of 69.31° C. (the freezing point of pure stearic acid) by the sealed tube method.

Example II

65.16 grams of the same commercial stearic acid used in Example I and 3.6 grams of pure acetamide were dissolved in about 16 grams of warm benzene. Crystallization was initiated by cooling the solution to room temperature. The crystals, stearic acid-acetamide, were separated from the mother liquor by centrifugation and were desolvanted. The nitrogen content of the product by the Kjeldahl method was 4.18%. The theoretical nitrogen content of stearic acid-acetamide is 4.08%. The stearic acid-acetamide product was then extracted with hot water and the resulting stearic acid, 12.6 grams after desolvantizing, had an iodine value of 0.4.

Example III

30 grams of a commercial palmitic acid (containing a few mole percent of homologous fatty acids and having a freezing point by the sealed tube method of 61.38° C.) and 6.9 grams of pure acetamide were melted together and recrystallized twice from 15 cc. portions of a solvent consisting of 2 parts by volume of benzene and one part of acetone, the crystals being separated by centrifugation. The yield was 23.5 grams. The freezing point by the cooling curve method was 58.0° C.

Four additional recrystallizations from about 7 cc. portions of the same solvent gave about 12 grams of white crystalline palmitic acid-acetamide having a freezing point by the cooling curve method of 58.8° C.

Example IV

30 grams of commercial palmitic acid similar to that used in Example III and 6.9 grams of pure acetamide were dissolved in 15 cc. of warm benzene. The crystals which formed on cooling to room temperature were separated by exhaustive centrifugation and recrystallized eight more times from 15, 12, 11, 9, 11, 12, 12, and 15 cc. portions of benzene, respectively, yielding 18.2 grams of crystalline palmitic acid-acetamide having a freezing point by the cooling curve method of 58.4° C.

This palmitic acid-acetamide was extracted with water yielding 13.2 grams of palmitic acid. Traces of acetamide were removed by recrystallizing the palmitic acid five times from approximately 5 cc. portions of pure acetone, giving 10.5 grams of pure palmitic acid having a freezing point by the Francis and Collins cooling curve method of 62.45° C. (the freezing point of pure palmitic acid).

Example V

104 grams of a commercial palmitic acid similar to that used in Example III and 26 grams of pure acetamide were dissolved in 32 grams of a warm solvent consisting of 2 parts by volume of benzene to 1 part of acetone, and the crystals, palmitic acid-acetamide, which formed on cooling to room temperature were separated by exhaustive centrifugation. They were then recrystallized 19 more times from portions of the same solvent, successive portions used decreasing gradually from 30 to 10 cc.

The recrystallized palmitic acid-acetamide, of which there was 24.5 grams, had a melting point of 58.4° C. by the cooling curve method and a nitrogen content of 4.40%. The theoretical nitrogen content of palmitic acid-acetamide is 4.44%.

The process of the above examples is also applicable to the purification of other long chain fatty acids. For example, by the procedure exhibited by Example II, the process of the invention can suitably be utilized in the purification of unsaturated fatty acids such as oleic and elaidic acids ($R=C_{17}H_{33}$) and mixtures containing them.

In addition, although in the above examples the process of the invention has been used to isolate individual fatty acid-acetamide compounds, it is also useful in the isolation of mixtures of such compounds. For example, many of the so-called double- and triple-pressed stearic acids, which are familiar articles of commerce, are actually palmitic and stearic acids mixed with small amounts of unsaturated fatty acids, such as oleic acid. For various purposes (e. g. in the production of cosmetics) such fatty acid mixtures, when substantially freed of unsaturated components have markedly greater value.

Therefore, a means of isolating the saturated acids from the unsaturated ones has considerable utility. The present invention provides such a means. For example, by dissolving such a mixture of fatty acids in a solvent such as acetone or a hydrocarbon and dissolving the required amount of acetamide in the resultant solution, a crystalline material predominating in stearic acid-acetamide crystals mixed with palmitic acid-acetamide crystals may be obtained. Thus the proportion of unsaturated acids present in the initial material can readily be lowered. The

proportion of unsaturated acids can be reduced substantially to zero, if desired, by further recrystallization of the mixed fatty acid-acetamide compounds.

Acetone is a good solvent to use in purifying the crystalline material by a recrystallizing procedure. For example, 20 grams of an impure sample of

was recrystallized four times from 8 to 10 cc. portions of pure acetone yielding about 10 grams of palmitic acid-acetamide having a freezing point by the cooling curve method of 58.6° C.

The process also provides an improved and simplified method of identifying long chain fatty acids. Even where the homologs of a given acid are present in the mixture in significant amounts, the acid present in a predominant amount can readily be isolated by the process.

In addition, since acetamide forms with the long chain fatty acids distinct compounds of the formula

and such compounds are partially dissociated in solution, the process of the present invention can be employed in the separation of mixtures of acids by partition chromatography.

The long chain fatty acid-acetamide compounds are formed by mixing the acid and amide to form a liquid single phase solution and causing crystallization to take place. Such compounds are partially or completely dissociated when they are melted or dissolved. Whether such a compound can be isolated from a given liquid single phase solution depends upon the acid involved, the molar amounts of acid and acetamide present in the solution and to some extent upon the character of the solvent.

In a simple case in which the solution consists of a molten mixture of the long chain fatty acid and the acetamide, if crystallization is caused to take place by cooling the solution to a temperature at which the solid and liquid phases are in equilibrium with each other and below which substantially all of the liquid phase solidifies, in the case of stearic acid, the crystals will all be the stearic acid-acetamide compound as long as the solution contained from 34.6 to 61.6 mole percent of acid before cooling.

The same considerations apply in the case of the following acids where the mole ratio of acid and acetamide in the solutions are between the mole ratios indicated under A and B below:

50	Acid	A		B	
		Mole percent acid	Mole percent acid	Mole percent acid	Mole percent acid
55	Stearic	34.6	61.6		
	Palmitic	38.2	64.8		
	Myristic	42.7	69.0		
	Lauric	45.8	75.8		
	Oleic	60.8	85.0		
	Elaidic	52.8	65.8		

Solutions in which the mole ratio of acid and acetamide are between ratios A and B are solutions the freezing points of which form the portion of the freezing point diagram of the acid-acetamide system in which the acid-acetamide compound can be the only solid phase in equilibrium with the liquid, i. e., points A and B indicate the mole ratios either of eutectic mixtures or solutions which can exist in equilibrium with the solid phases at the incongruent melting point of the acid-acetamide compound.

In the case of solutions of stearic acid and acetamide in which the mole percent of the acid is less than about 47%, crystals of the stable solid modification of acetamide can be formed. The formation of such crystals can readily be avoided by the conventional procedures for obtaining the desired crystals from such a binary system, for example, by heating to from about 10 to 20° C. above the freezing point and cooling relatively rapidly. In addition, it will be apparent to those skilled in the art, from the

shape of the freezing point diagrams, that the acid-acetamide compounds can feasibly be produced from solutions in which the amount of acid present varies beyond the limits designated under A and B above. In these cases, the crystals which form first are the acid or acetamide, but eventually the crystals of the acid-acetamide compound, in eutectic proportion with the acid or acetamide crystals, are formed.

In the more complex systems in which the liquid single phase solution contains a solvent and/or minor amounts of other acids in addition to the acid which it is desired to crystallize as the acid-acetamide compound, the total acid and amide should be present in substantially the same range of proportions, lying between the ratios indicated under A and B above. The range usually narrows slightly as the proportion of solvent increases. In general, it is preferable to dissolve the acid and the acetamide in substantially equimolar proportions where the liquid single phase solution contains a solvent.

Alternatively, in purifying acids by the process of this invention the fatty acid-acetamide compounds can feasibly be produced from liquid single phase solutions in which the mole ratio of acid to acetamide is less than that indicated under A above. In such cases acetamide is the first compound to crystallize but as the temperature is lowered a mixture of acetamide and the acid-acetamide compound begins to crystallize in the form of a mixture of crystals in approximately the eutectic proportions. The acid-acetamide compounds so produced in admixture with acetamide are acid-acetamide compounds of the acid which was present in predominant proportions in the original mixture of acids. The predominant acid present in a mixture of acids can thus be recovered in a pure form, for example by dissolving the mixture of acids with a molar portion of acetamide greater than the proportion present in either the acid-acetamide compound-acetamide eutectic mixture or the solution which can exist in equilibrium with the solid phases at the incongruent melting point of the acid-acetamide compound (i. e., proportions of acetamide greater than those indicated under A above) in an amount of a solvent sufficient to dissolve them at an elevated temperature but insufficient to dissolve them at normal room temperature, cooling the resultant solution until the crystals which formed contain appreciable amounts of the acid-acetamide compound, isolating the crystals, and separating the acetamide from the acid, for example by contacting the crystals with water at a temperature above the melting point of the acid-acetamide compound until substantially all of the acetamide is dissolved in the water, and separating the insoluble acid from the resultant solution. In some cases, for example in cases in which the acid-acetamide compound exhibits an incongruent melting point, e. g. oleic, and elaidic acids, it is preferable to form the fatty acid-acetamide compounds from liquid single phase solutions containing the acid and acetamide in such mole ratios.

A suitable method of recovering a purified acid from a fatty acid-acetamide compound comprises contacting the acid-acetamide compound with a mixture of immiscible solvents, each of which is a selective solvent for one component of the compound, e. g. hydrocarbons such as hexane, benzene, and the like, mixed with water. It is advantageous to first contact the acid-acetamide compound with water at a temperature above the melting point of that compound and then to separate the acid from the resulting aqueous solution with the selected solvent for the acid.

Another suitable method of recovering a purified acid from a fatty acid-acetamide compound comprises removing the acetamide from the compound by distillation or sublimation preferably at reduced pressures.

I claim:

1. A crystalline compound having the formula

R corresponding to the hydrocarbon radical attached to the carboxyl group of a long chain fatty acid.

2. A compound according to claim 1, wherein the acid is saturated.

3. A compound according to claim 1, wherein the acid is selected from the class consisting of stearic acid, palmitic acid, myristic acid, lauric acid, oleic acid, and elaidic acid.

4. A crystalline compound having the formula

5. A crystalline compound having the formula

6. A crystalline compound having the formula

7. A crystalline compound having the formula

8. A crystalline compound having the formula

9. A process of producing a crystalline compound comprising forming a liquid single phase solution containing a liquid organic inert solvent, a long chain fatty acid and acetamide, whereby the acid and the acetamide can form a crystalline compound having the formula

R corresponding to the hydrocarbon radical attached to the carboxyl group of the long chain fatty acid, and causing crystallization of the compound to take place.

10. A process according to claim 9, wherein the acid is saturated.

11. A process according to claim 9, wherein the acid is selected from the class consisting of stearic acid, palmitic acid, myristic acid, lauric acid, oleic acid, and elaidic acid.

12. A process according to claim 9, wherein the acid is stearic acid.

13. A process according to claim 9, wherein the acid is palmitic acid.

14. A process according to claim 9, wherein the acid is myristic acid.

15. A process according to claim 9, wherein the acid is lauric acid.

16. A process according to claim 9, wherein the acid is elaidic acid.

17. A process of separating a substantially pure long chain fatty acid from a mixture containing a predominant amount of such acid and lesser amounts of other long chain fatty acids comprising forming a liquid single phase solution containing the mixture and acetamide, causing a compound having the formula

R corresponding to the hydrocarbon radical attached to the carboxyl group of the long chain fatty acid being separated, to crystallize in the mother liquor, and separating the formed crystalline material therefrom.

18. A process according to claim 17, wherein the long chain fatty acid being separated is saturated.

19. A process according to claim 17, wherein the long chain fatty acid being separated is selected from the group consisting of stearic acid, palmitic acid, myristic acid, lauric acid, oleic acid, and elaidic acid.

20. A process of separating substantially pure stearic acid from a mixture containing a predominant amount of stearic acid and a lesser amount of other long chain fatty acids comprising forming a liquid single phase solution containing the mixture and acetamide, causing a compound predominately consisting of one having the formula

to crystallize in the mother liquor, and separating the formed crystalline material therefrom.

21. A process of separating substantially pure palmitic acid from a mixture containing a predominant amount of palmitic acid and a lesser amount of other long chain fatty acids comprising forming a liquid single phase solution containing the mixture and acetamide, causing a compound predominately consisting of one having the formula

to crystallize in the mother liquor, and separating the formed crystalline material therefrom.

22. A process of separating substantially pure stearic acid from a mixture containing a predominant amount of stearic acid and a lesser amount of other long chain fatty acids comprising dissolving the mixture and acetamide in an inert solvent, causing a compound predominately consisting of one having the formula

to crystallize in the mother liquor, and separating the formed crystalline material therefrom.

23. A process according to claim 22, wherein the other long chain fatty acids include palmitic acid and oleic acid.

24. A process according to claim 22, wherein the inert solvent includes benzene, the solution of the mixture of stearic acid and other long chain fatty acids and acetamide in the solvent is effected at a temperature above room temperature, and the compound having the formula

is caused to crystallize in the mother liquor by lowering the temperature to room temperature.

25. A process according to claim 24, wherein the mixture of stearic acid and other long chain fatty acids is mixed with acetamide in the inert solvent in substantially equimolecular proportions based upon the neutralization value of the mixture of acids.

26. A process of producing a compound of the formula $C_{17}H_{35}COOH.NH_2COCH_3$ which comprises, forming a liquid single phase solution consisting of molten stearic acid and acetamide containing from 34.6 to 61.6 mole percent stearic acid, causing crystallization of the compound to take place by cooling the solution to a temperature at which both solid and liquid phases are in equilibrium and below which substantially all of the liquid solidifies, and removing the crystals.

27. A process of separating a substantially pure long chain fatty acid from a mixture containing a predominant amount of such an acid and a lesser amount of other long chain fatty acids which process comprises: dissolving the mixture and a molar proportion of acetamide greater than the proportion present in either the acid-acetamide compound-acetamide eutectic mixture or the solution which can exist in equilibrium with the solid phases at the incongruent melting point of the acid-acetamide compound in an amount of a liquid hydrocarbon sufficient to dissolve them at an elevated temperature but insufficient to dissolve them at normal room temperature, cooling the resultant solution until the crystals which form contain appreciable amounts of an acid-acetamide compound, isolating the crystals and contacting them with water at a temperature above the melting point of the acid-acetamide compound

until substantially all of the acetamide is dissolved in the water, and separating the insoluble acid from the resultant solution.

28. A process of separating a substantially pure long chain fatty acid from a mixture containing a predominant amount of such acid and lesser amounts of other long chain fatty acids comprising forming a liquid single phase solution containing the mixture and acetamide, causing a compound having the formula

R corresponding to the hydrocarbon radical attached to the carboxyl group of the long chain fatty acid being separated, to crystallize in the mother liquor, separating the formed crystalline material therefrom, contacting the separated crystalline material with a liquid in which acetamide is soluble and the acid being separated is less soluble than acetamide, whereby the crystalline material dissociates into the acid and acetamide, the acetamide dissolves and the acid is undissolved, and isolating the undissolved acid from the resultant solution of acetamide in said liquid.

29. A process according to claim 28 wherein the liquid is water.

30. A process according to claim 29 wherein the long chain fatty acid being separated is stearic acid.

31. A process according to claim 29 wherein the long chain fatty acid being separated is palmitic acid.

32. A process of separating substantially pure stearic acid from a mixture containing a predominant amount of stearic acid and a lesser amount of other long chain fatty acids comprising dissolving the mixture and acetamide in benzene at a temperature above room temperature, lowering the temperature to room temperature to cause crystallization in the mother liquor of a compound having the formula

separating the formed crystalline material therefrom, contacting the separated crystalline material with water, whereby the crystalline material dissociates into stearic acid and acetamide, the acetamide dissolves and the stearic acid is undissolved, and isolating the undissolved stearic acid from the resultant solution of acetamide in water.
